T. P. LALLANCE

SHOE RACK

Filed July 3, 1922

T.P. Lallance, Inventor

By C. Snowdon
Attorney

UNITED STATES PATENT OFFICE.

THEODORE P. LALLANCE, OF HUNTINGTON, WEST VIRGINIA.

DESIGN FOR A SHOE RACK.

Application filed July 3, 1922. Serial No. 2,931. Term of patent 7 years.

To all whom it may concern:

Be it known that I, THEODORE P. LALLANCE, a citizen of the United States, residing at Huntington, in the county of Cabell and State of West Virginia, have invented a new, original, and ornamental Design for Shoe Racks, of which the following is a specification, reference being had to the accompanying drawing, forming part thereof.

The figure is a perspective view of a shoe rack, showing my new design.

I claim:—

The ornamental design for a shoe rack, as shown.

THEODORE P. LALLANCE.
